UNITED STATES PATENT OFFICE

158,455

CHARIOT TYPE TRICYCLE

Theodore D. Glamb, Wayne, Mich., assignor to
Dual Remote Control Co., Inc., Wayne, Mich.,
a corporation of Michigan

Application November 3, 1947, Serial No. 142,275

Term of patent 14 years

(Cl. D34—15)

To all whom it may concern:

Be it known that I, Theodore D. Glamb, a citizen of the United States of America, residing in the county of Wayne and State of Michigan, have invented a new, original and ornamental Design for a Chariot Type Tricycle, of which the following is a specification, reference being had to the accompanying drawing, forming a part thereof, wherein:

Figure 1 in the drawing is a perspective view of a chariot type tricycle showing my new design, and

Figure 2 is another perspective view taken from a different angle.

The characteristic features of my design are illustrated by the solid lines in the drawings.

I claim:

The ornamental design for a chariot type tricycle, substantially as shown and described.

THEODORE D. GLAMB.
